PUMP DEVICE

Douglas Johnston, Alexandria, Va.

Application July 2, 1945, Serial No. 602,735

5 Claims. (Cl. 103—44)

1

This invention pertains to liquid pumps generally, and concerns itself more particularly with a rodless deep well pump.

It is the general aim of the invention to provide an improved pump of the type mentioned having a minimum number of parts arranged in the most effective manner to reduce substantially its weight, pipe diameters, and cost over all presently known devices of this sort, without sacrificing any of its efficiency.

More specifically, it is a purpose of the instant invention to provide an improved subsurface pump unit in which only one casing is employed.

It is a further object of the invention to provide an improved subsurface pump unit equally adaptable to the use of either a spring or air motor.

It is also an object of the invention to provide a pump possessing an improved power unit having a minimum number of working parts which may be used in conjunction with an improved surface unit to accomplish the foregoing objects of invention.

These, and other objects, will become apparent as the description proceeds, and the scope of the invention will be pointed out in the appended claims. A more comprehensive understanding of the invention will be afforded from the following detailed description when considered in conjunction with the accompanying drawings in which:

Fig. 1 is a plan view in partial section of a power unit forming a part of the instant invention;

Fig. 2 is a vertical sectional view of the power unit taken along the line 2—2 of Fig. 1;

Fig. 3 is a partial sectional view of the power unit taken along the line 3—3 of Fig. 2 and looking into the hydraulic section thereof;

Fig. 4 is a vertical sectional view of the subsurface unit embodying the instant invention;

Fig. 5 is a cross-sectional view of said subsurface unit taken along the line 5—5 of Fig. 4;

Fig. 6 is a similar view taken along the line 6—6 of Fig. 4;

Fig. 7 is a schematic layout of the entire pump assembly showing the subsurface unit, the power unit, and its connecting conduit;

Fig. 8 is a vertical sectional view showing a modification of the subsurface unit illustrated in Fig. 4; and

Figs. 9—13, inclusive, are cross-sectional views of the unit illustrated in Fig. 8 taken, respectively, along the lines indicated.

2

Like reference numerals have been used throughout in the drawings to designate like parts.

Referring now to the drawings, particularly Fig. 7, the invention in its preferred embodiment comprises a power unit 8, a subsurface unit 9, and a connecting conduit 10.

The power unit 8 is intended to apply power to the subsurface unit 9 through the medium 10 of the liquid column carried in the conduit 10 in a manner such that the subsurface unit is made operative to lift the fluid into which it is submerged. It comprises a crankcase 11 which is removably connected to a pump housing 12 by means of a plurality of bolts 13. A crankshaft 14 is mounted for rotation within the crankcase 11 in a pair of bearings 15 carried in the walls thereof. A connecting rod 16 gives reciprocatory motion to a cross slide 17 by power from the crankshaft 14. A main bearing 18 and a wrist pin 19 form the usual connecting members for this rod. A pair of journal plates 21 and an end plate 22 secured to the walls of the casing 11 provide means for easy access to the working parts of the power unit.

A piston 23 movable in a cylinder 24 in the pump housing 12 is driven by the cross slide 17 connected thereto by means of a piston rod 25 which is slidable in a guide 26 and a packing head 27. The pump housing 12, in which the cylinder 24 is fashioned, has an outlet connection 28 fashioned thereon communicable with the cylinder 24 by means of a port 29. Into this connection is screwed the conduit 10 connecting the power unit 8 with the subsurface unit 9. A cylinder head 31 fitted into the pump housing 12 closes the cylinder 24.

The remaining interior portions of the pump housing 12 are devoted to a series of valves and interconnecting ports operable to apply power to the pressure column of liquid at the proper portion of the stroke of piston 23 and to discharge the liquid to the outlet of the pump and into the tank where it is intended to be used.

As a part of this system, a port 32 is opened into the cylinder 24 and connects with a port 33 also opening into the cylinder 24 but behind the piston 23. These ports are interrupted by a valve 34 which is operable upon the compression stroke of the piston 23 and closable upon the return stroke thereof. The valve 34 seats against flanges on the internal partitions 35 of the pump housing 12 which separate the ports 32 and 33 from a valve cavity 36. Connected to this cavity is a second valve cavity 37 which is separated from

the port 32 by a pressure diaphragm 38. A valve 39, movable in the valve cavity 37, seats itself against a partition 41 therein, which divides the valve cavity into an upper and lower section. The valve 39 is attached to the pressure diaphragm 38 by means of a valve stem 42. The valve stem 42 is provided with a head 43, which extends through the partition 41 and is surrounded by a valve spring 44 operative against the head 43 to urge the valve closed against the retentive force of the pressure diaphragm 38. Openings 45 in the partition 41 provide a means for the flow of fluid from the upper to the lower sections of the valve cavity 37. The upper section of this cavity is connected by means of a port 46 with a third valve cavity 47 in which a check valve 48 is operative.

The valve cavity 47 is likewise divided into an upper and a lower section by means of a partition 49. Against this partition the valve 48 seats itself through the action of a valve spring 51. Ports 52 in the partition 49 render the valve 48 subject to fluid pressures occurring in the lower section of the valve cavity 47, and through these ports fluid is forced against the valve 48 to open the same. The upper section of the valve cavity 47 is connected with an outlet connection 53 by means of a port 54. To the outlet connection 53 is connected a pipe 55 which connects the pump with a pressure storage tank, not shown. The removable heads 56 in the pump housing 12 render the valve mechanisms accessible for repair.

The subsurface unit 9 is connected to the power unit 8 and, through the medium of the column of liquid carried in the conduit 10, is operable to lift the water from the well. This unit comprises a casing 57 to which the conduit 10 is connected by means of a connection 58. A sump section 59 is secured to a connection 61 by bolts 62, and this connection in turn is screwed onto the casing 57.

Operating within the bore 63 of the casing 57 is a lift mechanism comprising a piston 64 movable under the pressure of liquid in pipe 10 against the tension of a compression spring 65. The latter element surrounds a tube 66 which provides a passage for fluid from the sump section 59 to the bore 63 through a valve 67. Although a spring 65 is here illustrated, it is to be understood that an air motor may also be used with good results.

The force-producing movement of the piston 64 is transmitted to the spring 65 through a spring cap 68 into which the tube 66 is screwed. A stud 69 serves as a ridged connecting member between the piston 64 and the spring cap 68 and provides a retainer for a valve spring 71 which acts to maintain the valve 67 closed against its seat on top of the spring cap 68.

In a shouldered recess 72 in the lower extension of the spring cap 68, one end of the spring 65 is cradled; the other end thereof rests in a recess 73 provided in the connection 61. In this manner, a chamber 74, occupying the space between the outer walls of the tube 66 and the inner walls of the casing 57, is formed in which the spring 65 is retained. A number of holes 75, bored in the cap 68, provide openings through which fluid may pass from the chamber 74 into another chamber 76. Other holes 77 extending through the top of the cap 68 form ports which are closed by the valve 67 and through which fluid is passed from the tube 66 to the chamber 76.

For the release of high pressure fluid trapped under the piston 64 on its downward stroke, a valve 78 is provided. This valve covers several holes 79, bored through the piston 64, which com-

municate with the chamber 76 by means of a secondary port 81 and the holes 82. A valve spring 83 retained on a valve stem 84 urges the valve 78 to close the holes 79.

It will be apparent to those skilled in the art that as the depth of the well is increased the strength of the spring 65, and incidentally its size, will necessarily have to be increased. Eventually, a point will be reached where the spring volume within the chamber 74 will become so large that its effect on the chamber space will be noticeable. In such event, it is preferable that the spring be retained in a position outside of the chamber. A subsurface unit, modified to this extent, is illustrated in Fig. 8. This unit comprises a casing head 85 into which the conduit 10 is screwed. A short pipe section 86 of suitable diameter is also connected to this head. Within this section of the unit, a piston 87, which is similar to the piston 64 in the previously described modification, is operative. To the piston 87 is rigidly attached a tube 88 which serves a slightly different purpose than that of the tube 66 of the other unit. This tube is movable through a collar 89 which is rigidly held in a connection 91 attached to the lower extremities of the pipe 86. The collar 89 contains apertures opening into a chamber 92 formed by the internal walls of the pipe 86 and the external walls of the tube 88.

Within the connection 91, a bore 93 provides a cavity in which a valve 95 is operative, the latter element being urged against its seat by a spring 96 retained against the collar 89 and encompassing the tube 88. The tube 88, which is movable within the collar and its associated mechanisms, terminates in a crosshead 97, which is movable with the tube. A sump section 98 is screwed to a pipe 99 which is connected to the lower extremity of the connection 91. Suitable vertical slots made in the pipe 99 form runways for the block 97 to which is attached a circular spring retainer 102. A similar retainer 103 screwed to the pipe 99 forms, with the retainer 102, seats for a pump spring 104 encompassing the pipe 99. A length of lightweight casing 105, such as galvanized iron gutter pipe, extending from the retainer 103 to the connection 91, forms an enclosure for the spring 104.

A valve 107 is operative in the piston 87, which performs the same function as the valve 78 in the previously described embodiment.

Since the fundamental principles under which both of the illustrated subsurface units operate are the same, only the first will be described in connection with the system's operation. The essential differences, aside from the mounting of the spring outside of the compression chamber, lie in the operation of the valve 95. In this particular embodiment, this valve does not move with the tube 88. It is opened, however, by a reduction in pressure in the chamber 92. Here, also, the fluid from the source is admitted to the chamber 92 around the tube 88 rather than through it. These differences are minor and will not be discussed further.

The dimensions of the various parts of both units are not critical, although the pistons 23 and 64 normally are of the same diameter, and the outside diameter of the tube 66 is equal to that of the rod 25.

With the above-described arrangement, the entire lift assembly, including the piston 64, the spring cap 68 and the tube 66, are movable within the bore 63 of the casing 57. Through this action, liquid may be raised from a subterranean

area in a manner now to be described in connection with the operation of the pump.

Operation

As is shown schematically in Fig. 7, the subsurface unit is installed in the well with the tube 66 submerged to a suitable depth in the water, or other fluid to be pumped. The power unit 8 occupies a position above ground and is connected as previously described with the subsurface unit 9.

Assuming the pump system to be fully primed, that is, all of the ports, cavities and channels of both the power and subsurface units to be filled with fluid, then, on the compression stroke (to the left) of the piston 23, the fluid in the conduit 10 is placed under pressure. Fluid is also displaced into the port 32, and the force thereof opens the valve 34 to admit fluid into the chamber 36 and in the back of the piston through the port 33. Thus, the pressure of the fluid acting above and below the pressure diaphragm 38 is equal and the valve 39 is maintained closed by the spring 44, allowing a volume of fluid equal to the displacement of the piston rod 25 to be forced into the unit 9 through the pipe 10.

As pressure is thus exerted against the piston 64, it is forced downwardly to compress the spring 65. The force exerted by the fluid acting against the face of the piston 64 raises the pressure of the fluid in the chamber 74 surrounding the spring 65 to a value higher than that of the pressure of the fluid in the chamber 80, due to the differences in sizes of the areas against which the pressures are active. Hence, the pressure of the fluid in the chamber 74 (and 16, Fig. 4) is sufficient to open the valve 78 and allow it to discharge into the chamber 80 above this valve.

After the compression stroke of the piston 23 is ended and it reverses its direction toward the right to begin its suction stroke, the valve 34 closes and a pressure is built up in the port 36 which acts against the upper face of the pressure diaphragm 38, distending it downwardly. Under this action, the valve 39 is opened and fluid is forced through the port 46, the cavity 47, the check valve 48 and out through the pipe 55 to a pressure storage tank (not shown).

During the occurrence of the action just described with regard to the power unit on its suction stroke, the pressure above the piston 64 in the subsurface unit drops and the spring 65 acts to lift the piston. As the piston 64 rises, the valve 78 is closed, and the fluid retained above it is forced upwardly to maintain the system filled during the suction stroke of the piston 23.

Also, and on the upward stroke of the piston 64, a partial vacuum is created in the chamber 74, which causes the valve 67 to open. This permits fluid to flow from the well through the sump 59 and the tube 66 into the chamber 74 to complete one pumping cycle.

It will be apparent to those skilled in the art that the operation of the above-described pump system is dependent upon the premise that all of the passages, ports, cavities, etc. are continually filled with the fluid which is to be pumped. Since a certain amount of leakage is inherent in a system of this kind due to wear, faulty packings and so forth, it is necessary that some means be provided for keeping the system primed.

The pump itself is readily adaptable to a small diaphragm primer which, though not shown, may be described as follows: A small diameter tube connecting with the pressure tank is connected to a relief valve installed in the conduit 10. The

diaphragm of this valve is acted upon by a spring adjusted in such a manner that in the event the fluid pressure in the system falls below a predetermined amount, for example, five pounds per square inch, the spring overcomes the pressure of the fluid acting against the diaphragm and admits fluid from the pressure tank into the system by opening the valve.

Conversely, if the fluid pressure in the system should exceed a certain given pressure, for example, two hundred and fifty pounds per square inch, this pressure may be applied to the diaphragm to act against a heavier spring causing the same to open another valve which will allow the fluid to escape back to the pressure tank, which, by way of example, may be maintained at a pressure of approximately forty to sixty pounds per square inch.

Since the fluid pressure in the tank is fixed at a value so that only approximately two-thirds of the stored fluid can be used, there will always remain a sufficient amount of fluid to prime the system automatically even in the event the subterranean source is temporarily exhausted. With such a priming system, the pump may be placed in operation after installation by pouring a small amount of liquid, not to exceed ten or fifteen gallons, into the pressure tank.

Further, an air inductor or inspirator may be used to maintain a given air pressure in the storage tank. Accordingly, if the subterranean source of fluid is exhausted, the upper portion of the tank will be filled only with air until the automatic pressure valve shuts it off. If an outlet to the tank is open releasing some of this air pressure, the cycle will be repeated unless, in the meantime, the fluid level in the well has risen to a sufficient height, in which case normal operation of the system will be resumed.

In the priming of the system, it will possibly be wondered how the chamber 74 may be filled. This is provided for by drilling very small holes in the piston 64, which are not covered by the valve 78. Since the direction of flow through these holes reverses itself on each stroke of the piston 64, there is no danger of their clogging. Also, these holes are so small that leakage resulting from the operation of the piston will have no material effect on the operation of the pump.

While a preferred embodiment of the invention has been illustrated and described, it will be apparent that the same is subject to many modifications and, accordingly, it is intended that the representations herein made shall not be treated in a limiting sense and that the spirit and scope of the invention shall be defined only by the appended claims.

What is claimed is:

1. In a pump device in combination with a liquid source contact subsurface unit thereof, a power unit, and liquid conduit means connecting said units, said power unit comprising a housing having a cylinder therein, piston means movable within said cylinder, an outlet connection in said housing communicating with said cylinder, a by-pass port in said housing connecting the forward and rear sections of said cylinder whereby fluid may be passed on the compression stroke of said piston means to deliver fluid into the rear thereof, valve means for controlling the flow of fluid in said by-pass port, a pressure-responsive movable element, means connecting said cylinder and said by-pass port to deliver fluid pressure above and below said pressure-responsive movable element, a normally closed valve means connected

to and operable by said pressure-responsive element, port means connecting said by-pass port with a second outlet in said housing and check valve means interposed in said connecting port, said valve means in said by-pass port being opened upon a compression stroke of said piston means and said normally closed valve means being closed during said stroke to deliver a fluid under pressure at said first outlet, and said by-pass valve being closed upon the return stroke of said piston means whereby said normally closed valve means is opened to cause flow of a fluid to said second outlet.

2. In a pump device, a power unit comprising a housing having a cylinder therein, a piston movable within said cylinder, power means for imparting reciprocatory motion to said piston, connecting means within said housing for passing a fluid from the front of to the rear of said piston, valve means controlling the flow of fluid through said connecting means, a first outlet communicating with said cylinder forward of said piston, a second outlet communicating by way of said connecting means with said cylinder to the rear of said piston means, first and second valve means controlling the flow of fluid from the rear of said piston to said second outlet and pressure-responsive means for operating said first valve means whereby fluid is delivered under pressure to said first outlet upon a compression stroke of said piston means and whereby fluid is delivered under pressure to said second outlet upon a suction stroke of said piston means.

3. In a pump device, the combination of a power unit comprising a housing having a cylinder therein, a piston movable within said cylinder, power means for imparting reciprocatory motion to said piston, connecting means within said housing for passing a fluid from the front of to the rear of said piston, valve means controlling the flow of fluid through said connecting means, a first outlet communicating with said cylinder forward of said piston, a second outlet communicating by way of said connecting means with said cylinder to the rear of said piston means, first and second valve means controlling the flow of fluid from the rear of said piston to said second outlet, pressure-responsive means for operating said first valve means whereby fluid is delivered under pressure to said first outlet upon a compression stroke of said piston means and whereby fluid is delivered under pressure to said second outlet upon a suction stroke of said piston means, a subsurface unit comprising a casing, a piston movable within said casing and dividing the bore thereof into an upper and lower chamber, means connecting a fluid source with said lower chamber and movable with said piston, valve means in said connecting means for controlling the flow of fluid from said source into said chamber, valve means carried in said piston for controlling a flow of fluid from said lower to said upper chamber and openable upon an application of fluid under pressure to move said piston whereby the pressure of the liquid occupying said lower chamber is increased, means operative against said piston to return the same to its normal position upon a drop of pressure in the said upper chamber, and a liquid conduit connecting said power unit and said subsurface unit.

4. In a pump system, in combination, a power unit, a liquid source contact unit, and a liquid conduit connecting said two units, said power unit including a reciprocable piston and a cylinder, a liquid passageway leading from the cylinder at a point in front of said piston to the cylinder at a point behind said piston, a valve in said passageway biased to closed position adapted to be opened on the power stroke of said piston, a second liquid passageway leading to a discharge point from said first passageway at a point between said valve and the rear of the piston, a valve in said second passageway biased to closed position, and a diaphragm to which said last valve is connected having one face exposed to liquid in the passageway to one side of said first mentioned valve and the other face exposed to liquid in the passageway to the other side of said first mentioned valve, said liquid source contact unit including a casing, an apertured piston in said casing, a valve biased into a position to close the apertures in said piston, a liquid intake sump disposed at the lower end of said casing and connected thereto, a reciprocable liquid conduit in said casing and spaced from the wall thereof opening at its lower end into said sump, a valve at the upper end of said last named liquid conduit biased to closed position, said last named valve and last named conduit being connected to and movable with said apertured piston, a liquid chamber between said last two valves and surrounding said last named conduit, and means strongly biasing said connected valved piston and conduit to an upper position of movement, said biasing means exerting force enough to lift said connected valved piston and conduit and a predetermined head of water.

5. In a pump system, in combination, a power unit, a liquid source contact unit, and a liquid conduit connecting said two units, said power unit including a diaphragm and a valve connected thereto, reciprocable power means including a piston, means for effecting an equal pressure on both sides of said diaphragm on the power stroke of said reciprocable power means and for transmitting pressure into said liquid source contact unit, and means for increasing the pressure on one side of said diaphragm to open its connected valve effected on the return stroke of said reciprocable power means whereby pressure established in said liquid source contact unit is relieved and liquid is forced through said opened valve for discharge from said system.
